Fig. 1

Fig. 2

Fig. 3

FIGURE 1 is an isometric view of a color console table, showing my new design with the top in an open position;

FIGURE 2 is an enlarged fragmentary view of a portion of the reflecting surface on the underside of the lid; and

FIGURE 3 is another isometric view taken from the end opposite that shown in FIGURE 1 and with the hinged top in a closed position.

The dominant features of my design reside in the portion shown in full lines.

I claim:

The ornamental design for a color console table or similar article, as shown and described.
